(57) **CLAIM**

The ornamental design for a tire, as shown and described.

DESCRIPTION

FIG. 1 is a perspective view of a tire, it being understood that the tread is repeated throughout the circumference of the tire.

FIG. 2 is a front view of the embodiment of FIG. 1.

FIG. 3 is a right side view of the embodiment of FIG. 1, the left side view having similarly shaped and sized features as the right side view.

FIG. 4 is a cross-sectional view taken along line 4-4 of FIG. 2.

FIG. 5 is a cross-sectional view taken along line 5-5 of FIG. 2.

FIG. 6 is a perspective view of a tire, it being understood that the tread is repeated throughout the circumference of the tire, it being understood that the dashed lines show environmental features of the tire.

FIG. 7 is a front view of the embodiment of FIG. 6.

FIG. 8 is a right side view of the embodiment of FIG. 6, the left side view having similarly shaped and sized features as the right side view.

FIG. 9 is a cross-sectional view taken along line 9-9 of FIG. 7; and,

FIG. 10 is a cross-sectional view taken along line 10-10 of FIG. 7.

The dashed lines in the drawings denote environmental subject matter and do not form part of the following claim.
